UNITED STATES PATENT OFFICE.

WILLIAM HOOPES, OF WEST CHESTER, PENNSYLVANIA.

MACHINE FOR TURNING IRREGULAR FORMS.

SPECIFICATION forming part of Letters Patent No. 372,796, dated November 8, 1887.

Application filed April 25, 1887. Serial No. 236,122. (No model.)

To all whom it may concern:

Be it known that I, WILLIAM HOOPES, of West Chester, county of Chester, State of Pennsylvania, have invented a new and useful Improvement in Machines for Turning Irregular Forms, of which the following is a true and exact description, due reference being had to the accompanying drawings, which form a part of this specification.

My invention relates to machines for turning irregular forms, and especially for turning wagon and carriage spokes; and my object is to construct such machines so that their action shall be more nearly automatic than has heretofore been the case, and to generally improve their construction and mode of operation.

My invention consists in the devices, improvements, and combinations hereinafter fully described, and which are illustrated in the accompanying drawings, where they are shown in connection with a well-known form of machinery for turning irregular forms, and in which—

Figure 1 is a front elevation of my improved machine. Fig. 2 is an end elevation of the machine, taken at the left end of Fig. 1. Fig. 3 is an elevation of the other end of the machine. Fig. 4 is a cross section of my machine on the line $x-x$ of Fig. 1, looking toward the left. Fig. 5 is a section through one of my improved tracers on the line $y-y$ of Fig. 4; Fig. 6, a section of one of my guides on the line $z-z$ of Fig. 4. Fig. 7 is a perspective view of the left-hand end of my machine, showing the devices for controlling and stopping the forward motion of the carriage, causing the frame to move back from the cutters, and arresting the model in the desired position. Fig.

Fig. 8 is a side view of the cam-wheel, by means of which the mechanism which applies the device for stopping the model in a determined position is actuated. Fig. 9 is a view of the mechanism by which the carriage is caused to return to the starting-point and of the brake and its actuating mechanism; Fig. 10, an enlarged view of a portion of the device shown in Fig. 9; Fig. 11, a view of the levers shown in Fig. 10, on the section-line $v-v$ of said figure. Fig. 12 is an enlarged view of the shaft C^2 of Fig. 9, with its connected cranks. Fig. 13 is an enlarged view of the clutch and drum at

the left of Fig. 1, whereby at the end of the movement of the carriage the frame is thrown back from the cutters and the tension on the driving-belt released. Fig. 14 is a perspective view at the left of Fig. 1, showing a portion of the mechanism by which the motion of the carriage is made to change the speed of rotation of the work to arrest its own motion and to insure the stoppage of the model in correct position. Fig. 15 is an enlarged view of the sliding bar M of Fig. 1, which bar is secured in bearings in the frame of the machine and actuated by the movement of the carriage. Fig. 16 is a side view of my eccentric device for moving the dead-center holding the work in and out. Fig. 17 shows the mechanism which throws the driving-belts of the work-revolving gears in and out of operative connection in the position in which the belt-tightening pulleys are both out of operation, and Fig. 18 shows the same devices in the position occupied just before the pulleys are thrown to the non-operative position shown in Fig. 17.

A is the frame of the machine.

B are uprights, secured at their lower ends to a square shaft, C, and forming, with the square shafts D D, the frame for holding the work and model, D' representing the model, and D² the work. The devices by which the model and work are secured in the frame are old and well known, with the single exception of my improved double eccentric E¹, with straps and links e', connected with the spindle E' on each side, as shown, so that the downward movement of the lever e' will force the center point of spindle E' into the work with directness and precision. The spring e², connected with lever e', serves to press it downward and keep the center E' in place. The mechanism secured upon the work-holding frame, which serves to revolve the model and work, is of ordinary construction. The short upright B' is secured to the square shafts D D, and serves, together with the neighboring upright B, to support the journals of the short shafts S, F, and E. Upon the shafts S and E are secured gear-wheels F² F², these gears engaging with a pinion, F', on the driving-shaft F, which shaft receives its motion from a pulley-wheel, F³. The working-holding frame B C D D is movable, its motion being to and

from the cutters P and upon the journals of the square shaft C. The guides and tracers are supported in the ordinary way upon an upright bar or "stack," O², which is pivoted in 5 a bearing surrounding and concentric with the shaft C and moving along it as the carriage moves. A spring, O¹, (see Figs. 3 and 4,) is provided, which causes the guides and tracers to press against the model and work and follow 10 the movements of the work-holding frame.

All of the above-described structure is of ordinary construction with the exception of my use of the three square shafts C D D, forming the work-carrying frame. These shafts, 15 in combination with the uprights B B B', add greatly to the rigidity and stiffness of the frame, and hence effect an improvement both in the durability of the machine and the character of the work done by it.

O (see Figs. 1, 3, and 4) is the frame and carriage upon which the cutters P are supported. This frame is supported on tracks o o on the frame A of the machine. (See Fig. 4.) It is also, at its lower end, provided with a sleeve, 20 O', through which the shaft C passes, (see Fig. 3,) and it derives its motion from a screw-shaft, K'. In all of the above particulars the carriage O does not differ materially from those in use. The upper part of the carriage O, which supports the cutters, is a hollow frame, as shown in Fig. 1. The two side pieces of this frame are fitted to receive the bearings p, which sustain the shaft p', upon which are secured the cutters P and the driving-pulley P'. I make 25 each of these bearings p vertically and independently adjustable by means of a set-screw, as shown in the drawings, or any well-known equivalent device for such set-screw. By this means I am enabled to keep the shaft p' in correct alignment with the driving-shaft G, from 30 which, by means of the pulley P', (which is secured upon the square shaft G and attached to the carriage O, so as to move with it along said shaft,) the pulley P' is driven by means of a belt. This device of adjustable bearings for 35 the shaft p' also enables me to adjust the tightness of the driving-belt with great nicety, and has been found in practice to be a great improvement over the old devices, in which the 40 journals of the shaft p' were not adjustable.

The general plan of the guiding and tracing mechanisms, which, as I have already pointed out, follow the movements both of the cutter-carriage O and of the work-holding frame, is 45 of the usual type. I have, however, made an improvement in this part of the mechanism which I have found improves the character of the work, and at the same time avoids the necessity of so often changing the guides and 50 tracers, as is requisite with the old constructions. This improvement is shown in Figs. 4, 5, and 6, and consists of providing wearing-shoes Q², provided with tenons conforming 55 with a line of their wearing-faces, these tenons being adapted to slide in slots in the arms or levers to which the guides and tracers are 60 secured, and to be clamped in said slots at any

desired point by adjustable clamps, as shown in the drawings. The shoes are made considerably longer than has heretofore been the case 70 with the wearing-face of the guides and tracers, and as they become worn the clamp is loosened and the shoe moved slightly in the curved or straight slot and then reclamped therein, so as to present a new and unworn face to the model 75 or work, as the case may be.

The main driving-shaft of the machine is that indicated on the drawings (see Figs. 2 and 3) by the letter G. This shaft receives its motion through pulleys H, Fig. 1, and, as already 80 pointed out, communicates motion to the cutters by means of the pulley P', which turns with the shaft G while it moves along with the carriage O.

At one end of the shaft G pulleys G' G² are 85 secured, which, by intermediate gearing, are so connected with the pulley K upon the shaft K' as to actuate the shaft in the direction which causes the carriage O to move forward. (See Figs. 1 and 2.) At the other end of the driving-shaft is secured a pulley, K⁴, with belt running to a pulley, K⁵, at the other end of the shaft K', said belt, when tightened, being adapted to reverse the motion of the shaft K.

The pulleys G' G² are of different diameters, 90 and they connect, by means of belts g' g, with pulleys G⁴ G⁵, of different diameters, said pulleys being secured upon a sleeve running on the end of the shaft C. The outer end of this sleeve is provided with a pulley, J, preferably 95 of the cone form shown, a belt, J', connecting this pulley with a pulley, K, also preferably of the cone form shown, and this pulley K can be made to engage or disengage the shaft K' by means of the clutch k. The other end of 100 the sleeve secured to the pulleys G⁴ G⁵ is provided with a pulley-wheel, J², from which a belt, J³, communicates motion and power to the driving-pulley F', which, as I have already 105 explained, actuates the gearing which turns the model and work. It is, as is well known, necessary to change the speed of the cutters and of the carriage during the process of turning a spoke, the high speed which is suitable for the turning of the rounded portion of the 110 spoke not being suitable for the square end thereof. It is for this reason that the two sets of pulleys G' G² G⁴ G⁵ are provided, one pair 115 being for high and the other for low speed. The large pulley G² of the shaft G connects, by 120 means of the belt g, with a small pulley, G³, secured upon the shaft C, and the small pulley G' connects, by belt g', with the large pulley G⁴. Both these belts g g' run loosely on the pulleys, and to bring them to a driving tightness it is necessary to use a pressure pulley.

G⁵ and G⁶ (shown in Figs. 1, 2, 17, and 18) are tightener-pulleys provided for this purpose, G⁵ being adapted to press upon the belt g, and G⁶ to press upon belt g'. Generally 125 speaking, the arrangement which I have just described is old; but I believe it to be new with me to place both pressure-pulleys on the slack side of the respective belts upon which

they are intended to operate, and to secure the same upon a centrally-pivoted frame, G⁷, operated by means of a lever, G⁸, and connecting-rod g², as shown. As is shown in the drawings referred to, the upward motion of the lever G⁸ causes the pressure-pulley G⁵ to press upon the fast-running belt, while the downward motion of the lever lifts the pulley G⁵ out of contact with its belt and causes the pulley G⁶ to press upon the slow-running belt, the medium position of the lever relieving the pressure from both belts, so that no driving-power is applied to the pulleys G³ G⁴ from the shaft G.

The hereinbefore-described improvements can be used with advantage upon machines which have not the other and more radical improvements in their mode of operation, which I will now proceed to describe, although, as will be seen, they are well and, indeed, peculiarly adapted for use in connection with these other improvements.

It will be most convenient in describing my invention to consider the different parts as they would come into action during the turning of a spoke, although, as the apparatus is somewhat complicated, it may be necessary, for the sake of clearness, to depart somewhat from this plan.

To begin, then, the frame B B C D D is thrown away from the cutters when it is desired to insert a new blank, the frame moving forward or toward the spectator looking at the machine, as in Fig. 1. The blank E² is inserted and clamped between the live-spindle E and the dead-center E' by means of the cam E⁴, as already described. The carriage O being then at the extreme right of its throw, the operator takes hold of the lever L', (see Figs. 1 and 3,) and by its means turns the shaft L, to which it is attached. The crank-arm L², secured upon the shaft L, has attached to it a link or connecting-rod, L³, curved, as shown in Fig. 4, at the end attached to the crank L², and at its other end provided with a slot, l, which engages with a pin, l', on one of the uprights B of the work-holding frame. The revolution of the shaft L, acting through this crank-arm L² and link L³, throws the frame back against the cutters P. The function of the slot l in the link L³ is to permit of the normal oscillating or reciprocating movements of the frame holding the work without interfering with the shaft L. At the end of the shaft L is secured another crank-arm, L⁴, which, before the shaft L is turned by the handle L', is in the position shown in full lines in Fig. 17—to wit, with a pin or projection at its end, directly under a projection, i', of a rod, I. As the shaft L turns to throw the work-holding frame back against the cutters, this rod I is raised by the end of the crank L⁴ to the position shown in the dotted lines of Fig. 17 and in full lines in Figs. 2 and 7. The rod I is pivoted at its lower end to the free end of the lever G⁸, which, through the connection g², actuates the pressure-pulleys G⁵ G⁶, and, as shown in the drawings referred to, the elevation of the rod I upon the end of

crank-arm L⁴ raises the lever G⁸ and depresses the pressure-pulley G⁵, bringing the pulley into operative pressure upon the belt g, and thus setting the pulleys at the end of the shaft C into rapid motion through the high-speed pulley G³. This motion is communicated through the pulley J² and belt J³ to the driving-pulley F³, which, by means of its connected gearings, rotates the model and blank. The motion is also communicated through the pulley J and belt J' to the pulley K on the outer end of the shaft K'. 70 75

Referring now to Fig. 7, where it is most clearly shown, it will be seen that a spring, I', is secured upon the upper end of the rod I. The lower end of this spring is arranged so as to be but slightly above the level of the table when the rod I is in its highest position. On the outer edge of the table a slot, I², is provided, which permits the rod I to move to and fro across the table and prevents it from moving away from the table. As the rod I is elevated in this slot, the spring I' is pressed against the rod until its end comes above the level of the slot, when it springs out and against a lever, K², which is pivoted at k³ and connected at its shorter end with the clutch k. (See Fig. 1.) A light spring, k², serves to keep the clutch k disengaged before the spring I', being more powerful and acting against the spring k², throws it into connection with the pulley K. The action of the spring I' is such as to throw the lever K² over until it engages with the catch k', which retains the lever and clutch in position. The engagement of this clutch k, which is secured by a feather upon the screw-shaft K', causes the said shaft to revolve and the cutter carriage O to move forward, and the cutters P being always in operation the machine now is at full work and the process of cutting the spoke going on. 90 95 100 105 110

Upon the front edge of the frame or table A, I secure a bar, M, in suitable guides, which permit it to slide up and down the table. This bar is best shown in Figs. 14 and 15. An adjustable shoulder, M², in the present case, is adapted to engage with a projecting finger from the carriage O, (see Fig. 4,) so that the carriage in moving forward at a suitable time engages with the bar M and causes it to move forward with it. As the bar M moves forward its end m comes in contact with one arm of a bell-crank lever, M³, (see Fig. 7,) and as the bar continues to advance it causes the said lever to turn, and by means of its other arm, which presses against the outer edge of the rod I, pushes the said rod backward until it is thrown off of its resting-place on the end of the crank L⁴. A suitable slot being provided to permit the spring to clear the table in this position, the rod I falls of its own weight to the position shown in Fig. 18, carrying the lever G⁸ down with it, and through this lever throwing the high speed pressure-pulley G⁵ out of connection and the low-speed pressure-pulley G⁶ into connection, thus changing instantly both the speed of the revolution of the 115 120 125 130

model and blank and the speed with which the carriage O is advancing. This of course takes place at the end of the oval part of the spoke and when the machine is about to turn the 5 square portion thereof. I would also note at this point that the bell-crank lever M⁶ is provided with a spring, m⁴, which causes it to return to a normal position when the rod M is not in contact with it.

10 Upon the bar M is secured a spring-bolt, M¹, m⁴, and in connection with it a wedge, M². As the bar M continues to advance, the end of the spring-bolt M¹ comes in contact with the lever K², and its spring is compressed as the bar advances and until the wedge M², sliding underneath the lever K², lifts it out of its detent projection k', when the compressed spring flies rapidly out, throwing the lever with it and withdrawing the clutch k from the pulley K, 15 thus instantly stopping the advance of the carriage O. Before, however, the motion of the carriage is stopped the wedge-shaped adjustable appliance m³ passes beneath the arm N³ (see Figs. 7 and 14) and raises it and the shaft 20 N up to a height where the other end of the bar N³ is above the hook F⁶. The purpose of this will be more conveniently explained hereinafter.

Returning now to the movable frame of the 25 machine, it will be noticed that I continue the shaft E out beyond the frame and secure upon its end a cog-wheel, R. The end of the square shaft D, below the shaft E, is also correspondingly prolonged outside of the frame, and upon this prolongation, which is turned round, I secure another cog-wheel, R', and inside of it a drum, R², both running loosely upon the shaft. A clutch arrangement, r, is provided between the cog-wheel R' and the drum R², but is normally kept disengaged by means of a spring, 30 V. (See Fig. 13.) The cog-wheel R' is of course kept in constant operation as long as the shaft E rotates. The pivoted lever V' is attached to a collar on the hub of the cog R', and at its lower end is pivoted to a rod, V², which said rod has a hook, u, at its end, passing around and outside of a projection, u', upon the lever K². (See Fig. 7.) Secured to the drum R² is a chain, R³, which passes around a 35 sprocket-wheel, R', said sprocket-wheel being permanently fastened upon the fixed frame of the machine and having secured upon it, or in such way as to move with it, a cam, R⁵. After passing from this sprocket-wheel, the 40 chain is continued downward and connected at its lower end with a lever, R⁶, which has a weight, R⁸, secured at the extremity of the same end to which the chain is attached, and a hook, R⁷, secured at its other end. As 45 will be noticed in Fig. 7, the movable work-holding frame has secured to it a curved arm, t, at the end of which is a roller, T, which is in contact with the cam R⁵ of the sprocket-wheel R'. In this same drawing will be noticed a bell-crank lever, W, pivoted upon an 50 arm, W', of the movable frame at a point, w. One arm of this bell-crank is adapted to en-

gage with a prolongation of the rod V². The other arm is adapted to come in contact with the stop W² under the conditions which I am about to describe.

Returning now to the operation of the machine, as the lever K² is thrown over, as already described, to release the clutch k and stop the motion of the carriage, the projection u' engages with the hook u of the rod V² and pulls the rod outward. This causes the pivoted lever V' to turn and press the cog-wheel R' in toward the drum R² until the clutch r is engaged. The drum R² then revolves with the 55 cog-wheel R' and winds up the chain R³. As the chain is wound up, it of course rotates the sprocket-wheel R' and cam R⁵. Said cam, pressing against the roller T forces the work-holding frame forward and away from the cutters, 60 and by means of the link L³, secured to the frame and to the crank-arm L², turns the shaft L back to the position in which we first considered it, the curvature at the end of the link L³, which connects with the crank L², permitting a greater revolution of the shaft than would be possible were the link straight. While the work-holding frame is being thrown forward in this way the chain is also elevating the end of the lever R⁶, to which it is attached, 65 and depressing the opposite end with its hook R⁷. This hook in its downward motion passes beneath the pin i on the rod I and engages it, as is shown in Fig. 18. As the work-holding frame is pressed forward by the cam, bell-crank 70 lever W approaches the stop W² on the main frame of the machine, and at the end of the throw of the frame the end of the bell-crank comes in contact with the stop and is turned by it, so that its other end, engaging with the 75 prolongation of the rod V², acts to press the said rod back to its first position. This throws the gear-wheel R' away from the drum and disengages the clutch r, the spring V also co-acting to accomplish the same result; and either 80 the bell-crank or spring could be used alone for this purpose. The disengagement of the clutch r permits the drum to revolve freely on its bearing, and the chain R³, by means of its own weight and the weighted lever to which 85 it is attached, runs rapidly downward, the lever R⁶ returning to its normal position and raising the rod I, and its attachments with it, to the position shown in Fig. 17, said position being that in which both of the pressure-pulleys G⁵ and G⁶ are out of operative contact with the belts g'g, and such being the case, of course the gearing driven from the pulley J² and that driven from the pulley J soon come to rest. Before, however, the driving-pulley 90 F³ and its attached gearing have come to a standstill they have another function to perform.

It will be noticed that in Figs. 1 and 8 a cam projection, f, is shown as secured upon 95 the gear-wheel F², and that in Figs. 1 and 14 there is shown a hook-like projection on the edge of the driving-pulley F³, (said projection being marked f'.) A spring-hook, F⁴, secured

to the frame of the machine, is adapted to engage with this projection f' under the following conditions, and for the purpose described.

Referring now especially to Figs. 7 and 14, it will be seen that I secure upon the frame of my machine an upright standard, N' , which supports the bearings of an upright shaft, N . This shaft is free to slide up and down to some extent in its bearings, but is provided with a spring, n , which keeps it normally in its downward position. At the upper end of the shaft N is a crank, to which is secured a projecting stop device, N^2 . At its lower end is a cross bar, N^3 , one end of which passes over the bar M and the other end across a projecting rod, F^5 , secured at one end to the spring-hook F^4 and having a hook, F^6 , at its other end. In normal position the cross-bar N^3 engages with this hook F^6 ; but, as I have already pointed out, it is raised up out of engagement with the hook by means of the wedge m^3 , which lifts it just at the end of the forward movement of the bar M . Now, as the work-holding frame is thrown forward, the cam f on the wheel F^2 comes in contact with the end of the stop projection N^2 as the wheel F^2 revolves, and each revolution of the wheel thus causes the shaft N , with its cross-bar N^3 , to turn in its bearings, the spring n serving to bring it back to its normal position when the cam passes out of contact with N^2 . Before the gearing (of which the wheel F^2 forms a part) comes to a rest the bar M is moved backward by means which I will hereinafter describe, and wedge m^3 thus withdrawn from beneath the cross-bar N^3 , permitting it to fall back to its normal position, when it engages with the hook F^6 , and when next oscillated by the contact of the cam f with the stop N^2 it throws the spring-hook F^4 forward close to the rim of the driving-pulley F^3 , so that when the projection f' comes in contact with the hooked end of F^4 it grasps it and stops the driving-pulley and all of the gearing driven by it in a fixed and regulated position. The model and work are by this means always stopped in the same position, so that the operator knows without examination exactly how to place the next blank in the machine.

Returning now to the operation of throwing the work-holding frame forward and away from the cutters, as this frame is moved away by the cam R^5 the supporting-shaft C turns with it. Attached to the end of this shaft C is a crank-lever, C' , rigidly secured upon the shaft C , and having at its upper end a bar, C^2 , projecting from it, as shown in Figs. 10 and 11. Across the top of this projection C^2 lies a rod or bar, C^3 , which is provided with a lug or projection, c' , preferably secured upon it so as to be adjustable, as shown in Fig. 9, and so placed as to engage the bar C^2 when said bar is in the position it occupies when the frame is against the cutters. (See Figs. 3, 10, and 11.) One end of this rod or bar C^3 is secured to a hanger, K^6 , which (see Figs. 3 and 9) is suspended on a projection

from the frame of the machine at k^8 , and has at its other end a pressure-pulley, K^5 . The other end of the bar C^3 lies across the path of the sliding bar M . As will be at once seen, (see Fig. 3,) the revolution of the shaft C and crank-lever C' will, by means of its engagement with the projection c' on the bar C^3 , draw the pressure-pulley K^5 against the belt k^4 , thus placing the pulley K^4 upon the shaft G and the pulley K^3 upon the shaft K' in operative connection and causing the shaft K' to turn in such wise as to move the carriage O back to place of beginning. As this carriage moves backward, it again engages the bar M through a stop, M^4 , (see Fig. 1,) and causes the said bar M to slide backward until a wedge, M^5 , at its end elevates the end of rod C^3 sufficiently to disengage the projection c' from the bar C^3 and lever C' , when the pressure-pulley K^5 is at once released from its operative contact with the belt k^4 .

In Fig. 9 the lever C' , bar M , bar C^3 , and the connected mechanism are shown in the relative positions they occupy when the carriage O has moved back to the place of beginning, the wedge-surfaces M^2 and M^6 have raised the bar C^3 high enough to elevate the lug c' above the bar C^2 , and the bar C^3 has moved forward, relieving the pressure of pulley K^5 on belt k^4 . It is while the various parts are in the position shown in Fig. 9 that the work-holding frame is thrown back into operative position, and of course the rod C^2 on lever C' will pass under lug c' without touching it, as the bar M is not withdrawn from under bar C^3 till the carriage O is well advanced on its forward movement. I have, however, made the back of lug c' curved, as shown in Fig. 9, so that even if the bar C^2 should strike against it in its backward movement (as would be the case, for instance, if the frame was thrown forward for any reason after bar M was withdrawn from under bar C^3) it would raise the bar C^3 and pass under said lug. I have found, however, that it is desirable to check the revolution of the shaft K' by means of a brake, and I therefore provide a braking device, the details of which are shown in Figs. 3, 9, 10, 11, and 12.

In a proper bearing upon the frame of the machine I secure what is in effect a bell-crank lever, C^5 . (See Figs. 9 and 12.) To the short arm or crank of this lever C^5 , I attach a bent bar or frame, C^6 , which passes beneath the pulley K^3 and supports a brake-shoe, C^7 . The other end of this rod C^6 is supported by means of a pin, c^8 , upon the rod C^3 . To the other or long arm of lever C^5 , I attach a bar, C^4 , which I provide with a detent, c^9 , adapted to engage with the cross-bar C^2 of lever C' . The length of the bar C^4 is adjustable by means of a screw at its end connecting with the crank-arm of C^5 . Now, as the work-holding frame moves away from the cutters, the lever C' , turning with it, will throw the rod C^2 forward and turn the crank C^4 , bringing the brake-shoe C^7 nearly, but not quite, into contact with the periphery

of the driving-pulley K³. This same motion of the lever C', as I have already explained, tightens the belt k' and sets the shaft K' in action to return the cutter-carriage to the place of beginning. The bar M having, as aforesaid, been engaged by the carriage O on its return motion, the wedge M⁵ at its end first lifts the bar C³, so as to disengage its projection c' from the cross-bar C² and free the pressure-pulley 10 K⁵. This elevation of the end of the bar C³, acting through the rod C⁴, which rests upon it, brings the brake-shoe C' into still closer proximity with the periphery of the pulley K³, and as the bar M continues to advance the wedge 15 M⁵, passing under the end of bar C³, raises it still higher and clamps the brake-shoe tight against the wheel, thus effectively checking its rotation and any further movement of the carriage O. When now it is desired to again 20 start the machine, and the work-holding frame is thrown back toward the cutters, the lever C', turning with the frame and toward the bell-crank C⁵, permits the rod C⁴ to move in the same direction, and the bell-crank C⁵ is thus turned, 25 and the brake-shoe C' drops away from the periphery of the pulley K³, permitting the shaft K' to revolve freely.

The operation of my machine is, by the above-described appliances, made automatic from the 30 beginning of each operation of turning a spoke until the return of the mechanism into position to begin the turning of another spoke, and the machine therefore requires much less attention from the operator than is the case with 35 any of the machines in use for similar purposes. Many of the devices by which I attain this desirable result can be modified in form, and for several of such devices other equivalent mechanism could readily be substituted. Many of such are also independently useful and essential, even if the machinery is not organized to be automatic in its actions to the same extent that I have shown and described.

45 Having now described my invention, what I claim as new, and desire to secure by Letters Patent, is—

1. In a machine for turning irregular forms, substantially as specified, the combination, with 50 the movable spindle or center E', of the double eccentric E⁴, having links e' e', secured to both sides of said spindle, and the actuating-lever e', all substantially as and for the purpose specified.

55 2. In a machine for turning irregular forms, substantially as specified, guides or tracers consisting of wearing-shoes having their surfaces prolonged and provided with tenons conforming in line with their wearing-faces, and 60 clamping arms or holders provided with slots curved or straight to conform to the tenons of the shoes and provided with adjustable clamps, whereby the shoes can be moved and secured at will in the clamping-arms, all substantially 65 as specified, so that the contact-surfaces of said guides or tracers can be adjusted to present

different wearing-surfaces to the model and blank.

3. In a machine for turning irregular forms, substantially as specified, the combination, 70 with the driving-pulleys G' G² and the belts g g', of the pressure-pulleys G⁵ G⁶, secured in a centrally-pivoted frame, G⁷, and placed, as shown and described, so as to act on the slack sides of belts g g', and mechanism for actuating said frame to bring the pressure-pulleys 75 into operation, as desired.

4. In a machine for turning irregular forms, substantially as specified, the combination, 80 with the driving-pulleys G' G² and the belts g g', of the pressure-pulleys G⁵ G⁶, secured in a centrally-pivoted frame, G⁷, and placed, as shown and described, so as to act on the slack sides of belts g g', the pivoted lever G⁸, connecting-rod g², and mechanism for actuating the 85 lever to bring the pressure-pulleys into operation as desired.

5. In a machine for turning irregular forms, substantially as specified, the combination of the rod I, pivoted on the free end of the lever G⁸, which controls the adjustment of the pressure-pulleys G⁵ and G⁶, substantially as specified, the guide slot I², secured on the frame of the machine, a stop or shoulder upon which the rod is sustained in its highest position, the bell-crank lever M⁶, and the sliding bar M, whereby the motion of the carriage is made to effect an immediate change in the speed of the machine at the desired point. 95

6. In a machine for turning irregular forms, substantially as specified, the combination of the rod I, having shoulder i', and pivoted on the free end of a lever, G⁸, which controls the adjustment of the pressure-pulleys G⁵ and G⁶, substantially as specified, the guide-slot I², 100 which limits the arc through which the rod I can turn on its pivot, and the crank-arm L⁴, secured on the shaft L and arranged to engage the shoulder i' of rod I and elevate the rod and its attached lever G⁸ when the shaft L is rotated to throw the frame into operative position with the cutters. 105

7. In a machine for turning irregular forms, substantially as specified, the combination of the rod I, having shoulder i' and pivoted on the free end of a lever, G⁸, which controls the adjustment of the pressure-pulleys G⁵ and G⁶, substantially as specified, the guide-slot I², which limits the arc through which the rod I can turn on its pivot, the crank-arm L⁴, secured on the shaft L and arranged to engage the shoulder i' of rod I and elevate the rod and its attached lever G⁸ when the shaft L is rotated to throw the frame into operative position with the cutters, the sliding bar M, actuated by the carriage, and the bell-crank lever M⁶, which, when pressed by the end of bar M, throws the rod I away from the crank L⁴, freeing the shoulder i' and allowing the rod and lever G⁸ to fall and change the speed of the 115 gearing in the frame. 120

8. In a machine for turning irregular forms,

substantially as specified, in combination with the rod I, pivoted on the free end of lever G⁸, which actuates and controls the adjustment of the pressure-pulleys G⁵ G⁶, the lever R⁶, having 5 a hook, R⁷, secured at one end in such manner as to engage a pin, i, on rod I when said rod is at its lowest position and the end of lever R⁶ is depressed, said lever having a weight, R⁸, secured at its other end in such 10 manner as to counterbalance the weight of rod I and its attachments, a cord or chain, R³, by which the weighted end of lever R⁶ is elevated, and the hook R⁷, engaged with pin i and mechanism for actuating said cord or chain.

15 9. In a machine for turning irregular forms, substantially as specified, the combination of the pressure-pulleys G⁵ G⁶, arranged to act upon the driving-belts g g', as specified, and actuated through a pivoted lever, G⁸, the rod 20 I, pivoted on the end of lever G⁸ and having a spring, I', secured to it, the clutch-lever K², actuating the clutch h, whereby the screw-shaft K' is engaged or disengaged, and the detent k', secured upon the frame A so as to engage and 25 retain the lever K² when forced over by spring I', all substantially as shown and described, so that the elevation of the rod I at the same time causes the engagement of a pressure-pulley with a driving-belt connected with and driving 30 the gearing of the work-holding or movable frame, and also, by means of its spring I', forces the clutch-lever K² over to engage the screw-shaft K'.

10. In a machine for turning irregular forms, 35 substantially as specified, the combination of the rod I, pivoted on the free end of lever G⁸, which actuates the pressure-pulleys G⁵ G⁶, substantially as specified, said rod having shoulder i', pin i, and spring I', the weighted lever 40 R⁶, having hook R⁷, and cord or chain R³, for actuating it, the shaft L, having crank-arm L⁴, the bell-crank lever M⁶, the sliding bar M, the frame A, having guide-slot L² and detent k', and the clutch lever K², all substantially as 45 and for the purpose specified, so that at the proper point in the travel of the carriage the bar M, acting through lever M⁶, will throw the rod I off the arm L⁴, allowing it to fall and change the speed of the gearing in the work- 50 holding frame, then, by means of hook R⁷, elevating rod I to a point where both pressure-pulleys will be disengaged and sustaining it there until the revolution of shaft L raises it again to its first position by means of crank 55 L⁴, said elevation bringing the force of spring I' to bear on lever K² to engage its clutch and force it into detent k'.

11. In a machine for turning irregular forms, substantially as specified, the combination of 60 the rod I, pivoted on the free end of lever G⁸, which controls the adjustment of the pressure-pulleys G⁵ G⁶, the weighted lever R⁶, having hook R⁷, adapted to engage with a pin on rod I, as specified, and a chain or cord, R³, to elevate it, a drum, R², running loosely on shaft D and attached to chain R³, a gear-wheel, R', also 65 loosely journaled on shaft D, and geared with

a pinion on a spindle, E, forming part of the mechanism which rotates the blank, a clutch, V, whereby the drum R² and gear-wheel R' are engaged, pivoted lever V', for engaging and disengaging the clutch V, bent rod V², having a projection, u, adapted to engage with a lug, u', on clutch-lever K², clutch-lever K², having lug u', arranged to engage projection u of rod V² and through it engage the clutch V when lever K² is thrown to disengage the clutch directly controlled by it, and mechanism, substantially as described, for disengaging clutch V and allowing the weighted lever R⁶ to fall and elevate rod I when the frame is thrown away from the cutters, all substantially as and for the purpose specified. 70 75 80

12. In a machine for turning irregular forms, substantially as specified, the combination of 85 the rod I, pivoted on the free end of lever G⁸, which controls the adjustment of the pressure-pulleys G⁵ G⁶, the weighted lever R⁶, having hook R⁷, adapted to engage with a pin on rod I, as specified, and a chain or cord, R³, to elevate it, a drum, R², running loosely on shaft D and attached to chain R³, a gear-wheel, R', also loosely journaled on shaft D and geared with a pinion on a spindle, E, forming part of the mechanism which rotates the blank, a clutch, 90 V, whereby the drum R² and gear-wheel R' are engaged, pivoted lever V', for engaging and disengaging the clutch V, bent rod V², having a projection, u, adapted to engage with a lug, u', on clutch-lever K², clutch-lever K², having 95 lug u', arranged to engage projection u of rod V² and through it engage the clutch V when lever K² is thrown to disengage the clutch directly controlled by it, and a bell-crank lever, W, arranged in connection with rod V² and a 100 stationary stop, W², so as to return rod V² to its first position and disengage clutch V when the frame is thrown away from the cutters, all substantially as and for the purpose specified. 105 110

13. In a machine for turning irregular forms, substantially as specified, the combination of drum R² and clutch mechanism for throwing it in gear by the disengagement of the lever K², which controls the clutch by which connection 115 is made between screw-driving shaft K and the pulleys K, arranged substantially as shown and described, the chain or cord R³, actuating the lever R⁶, as described, and the sprocket-wheel K⁴, having a cam, R⁵, adapted to engage 120 with the frame holding the model, &c., and thrust said frame away from the cutters when the clutch V is engaged, substantially as shown and described.

14. In a machine for turning irregular forms, 125 substantially as specified, the combination of the clutch-lever K², adapted to engage in a detent, k', in the frame of the machine, and the sliding bar M, having spring-bolt M' and wedge M², whereby the bolt M' is pressed against the lever K², compressing the spring m' as the carriage advances until the wedge M² releases the lever from detent k', when the spring forces the lever over quickly, releasing the clutch k. 130

15. In a machine for turning irregular forms, substantially as specified, the combination of clutch-lever K^2 , having spring k^2 , tending to hold the lever in position to keep the clutch K uncoupled, and the rod I , having spring I' , which, when said rod is elevated, presses against lever K^2 , overcoming spring k^2 and forcing the clutch k to engage.

16. In a machine for turning irregular forms, substantially as specified, the combination of the clutch-actuating lever K^2 , having spring k^2 , arranged to keep the clutch disengaged when the lever is free from its detent k' , the sliding bar M , having spring-bolt M' and wedge M^2 , for releasing the lever from its detent and throwing it rapidly to disengage the clutch, and the rod I , arranged in connection with the mechanism controlling the pressure-pulleys, substantially as specified, and having a spring, 20 I' , which engages the lever K^2 when rod I is elevated and forces it into the detent k' , all substantially as and for the purpose specified.

17. In a machine for turning irregular forms, substantially as specified, the spring-clutch F^4 , 25 having a hooked arm, $F^5 F^6$, and the driving-pulley F^3 , having a detent-lug, f' , secured near its periphery, in combination with a shaft, N , journaled in a frame, N' , so as to have a turning motion therein, and having a crank-arm 30 and stop, N^2 , at its upper end and a lever, N^3 , at its lower end, and a cam, f , secured on one of the gear-wheels of the work-holding frame, all substantially as shown and described, so that when the frame is moved away from the 35 cutters the said cam will come in contact with the stop on crank-arm N^2 , causing the shaft N to turn and drawing the clutch F^4 into position to engage the detent f' by means of the lever N^3 and the hooked bar $F^5 F^6$.

40. 18. In a machine for turning irregular forms, substantially as specified, the spring-clutch F^4 , and having a hooked arm, $F^5 F^6$, and the driving-pulley F^3 , having a detent-lug, f' , secured near its periphery, in combination with a shaft, 45 N , journaled in a frame, N' , so as to have both a turning and sliding motion therein, and having a crank-arm and stop, N^2 , at its upper end and a cross-bar or lever, N^3 , at its lower end, a cam, f , secured on one of the gear-wheels of 50 the work-holding frame, and so placed as to come in contact with and actuate the stop on crank N^2 when the frame is thrown away from the cutters, and a wedge secured on the sliding bar M , as specified, so as to elevate the 55 bar-lever N^3 above the hook F^6 before the cam f engages with the stop N^2 and to drop the said bar-lever, permitting it to engage the hook F^6 and apply clutch F^4 at a determined point in the backward movement of bar M , all substantially as shown and described, so that the motion of the gearing in the frame may be arrested in a fixed and determined position immediately after the driving-belts which 60 actuate it are released.

65. 19. In a machine for turning irregular forms, substantially as specified, the combination, with the frame $B B D D C$, which holds the

model and work and the mechanism for actuating them, and the shaft L , having handle-lever L' and lever L^2 , of the link or connecting-rod L^3 , having one end curved and attached to lever L^2 , so as to permit said lever to turn with shaft L to a line parallel to or below the line of the points of attachments of the link L^3 , and its other end provided with a slot, 70 l , adapted to engage with a pin, l' , on the frame, all substantially as shown and described, and so that the frame can be thrown toward the cutters by means of the rotation of shaft L , while at the same time the oscillations of the frame in following the model take place independently of and without moving the connecting-link L^3 .

20. In a machine for turning irregular forms, substantially as specified, the shaft L , having 85 handle-lever L' and levers L^2 and L^4 , the frame $B B D D C$, and the lever G^8 , actuating and controlling the pressure-pulley $G^5 G^6$, substantially as specified, in combination with the bent and slotted link L^3 and the rod I , pivoted on 90 the end of lever G^8 and provided with a stop, i , and guide-slot in the frame of the machine, all substantially as shown and described, so that the turning of shaft L by means of lever L' will simultaneously throw the frame toward 95 the cutters and apply the pressure-pulley to the driving-belt which actuates the gearing in said frame.

21. In a machine for turning irregular forms, substantially as specified, the shaft L , having 100 handle-lever L' and levers L^2 and L^4 , the frame $B B D D C$, the lever G^8 , actuating and controlling the pressure-pulley $G^5 G^6$, substantially as specified, and the lever K^2 , controlling the clutch which connects the carriage- 105 driving shaft K' and the pulleys which drive it forward, in combination with the bent and slotted link L^3 and the rod I , pivoted on the end of lever G^8 and provided with a stop, i , spring I' , and guide-slot in the frame of the 110 machine, all substantially as shown and described, so that the turning of shaft L by means of lever L' will simultaneously throw the frame toward the cutters, apply the pressure-pulley to the driving-belt which actuates the gearing 115 in said frame, and throw lever K^2 into position to engage clutch k and start the carriage on its forward travel.

22. In a machine for turning irregular forms, substantially as specified, the screw-shaft K' , 120 having pulley K^3 , geared with the driving-shaft G so as to be turned by said shaft in the direction to reverse the motion of carriage O , the suspended pressure-pulley K^5 , controlled by bar C^4 , having detent c' , adapted 125 to engage with lever C' , attached to shaft C of the frame, and the wedge M^5 on sliding bar M , all arranged substantially as shown and described, in combination with shaft C^5 , having crank-arms, as specified, rod C^4 , attached to 130 one of said crank-arms, and having detent c' , whereby it is engaged and drawn back by lever C' when the frame is thrown away from the cutters, rod C^6 , attached to the other crank

arm or shaft C⁵ at one end and resting on bar C³ at the other, said rod carrying a brake-shoe, C', and a wedge, M⁶, on bar M, situated behind and above wedge M⁵, all substantially as 5 and for the purpose specified, so that the throwing of the frame away from the cutters will, through lever C', at the same time apply the pressure-pulley K⁵ to belt k, causing the carriage to return, and by drawing the bar C⁴ 10 forward cause the shaft C⁵ to rotate, bringing the brake-shoe C' close to the pulley K³, the releasing of detent c' of bar C³ by the action of wedge M⁶ will, at the same time that it releases pressure-pulley K⁵, bring the shoe closer 15 to the pulley by elevating the end of the rod C⁶, resting on the rod C³, the further elevation of the rod C⁶, by means of wedge M⁶, will cause the application of the brake to pulley K³, and the throwing back of the frame and lever C' 20 toward the cutters will release the brake by allowing bar C⁴ to move forward, the shaft C⁵ to turn, and the shoe-carrying bar C⁶ to fall.

23. In a machine for turning irregular forms, substantially as specified, the combination of 25 the work-carrying frame supported and pivoted upon shaft C, having an arm, t, and the drum R², secured upon it and adapted to engage with the gearing of said frame by means of a clutch, V, and having also a lever, C', 30 engaged with a pressure-pulley adapted to engage the carriage-driving shaft, with a belt geared to drive it in the reverse direction, the belt-gearing connecting the gearing of the frame with the driving-shaft, said gearing being controlled by the pressure-pulleys G⁵ G⁶, 35 actuated by lever G⁸ and rod I, as specified, the cutter-carriage O, actuated by screw-shaft K', the clutch-lever K², controlling the clutch k, which connects the shaft K' with the forward driving-pulleys, the sliding bar M, having appliances, as specified, which operate successively to change the speed of the gearing in the frame to throw off the clutch k and in its return motion to throw off the pressure-pulley act-

ing to return the carriage to the starting-point, 45 the chain R³, attached to drum R² and lever R⁶ and passing over a cam sprocket-wheel, R⁴ R⁵, secured to the frame of the machine, the weighted lever R⁶, having hook R⁷, and the shaft L, having handle L', lever-arms L² and L⁴, 50 said shaft being connected with the movable frame by a link, L¹, all substantially as and for the purpose specified, so that the throwing of the movable frame toward the cutters by the rotation of shaft L causes the pressure-pulleys to engage the gearing of the said frame with the driving-shaft, and the driving-shaft K' to engage with the driving-pulleys, which drive it in the direction which causes the carriage O to move forward, said carriage in its 60 forward motion, and by means of bar M, first throwing down rod I and changing the speed of the gearing in the movable frame by means of the pressure-pulleys G⁵ G⁶, and then, by means of lever K², throwing out the clutch K, 65 releasing the shaft K' from the driving-pulley, and stopping the carriage, the throwing of lever K² engaging the drum R² and winding up chain R³, which rotates cam R⁵, thrusting the movable frame away from the cutters, and 70 lowering the hook R⁷ on weighted lever R⁶ to engage rod I, the motion of the movable frame releasing drum R² and allowing the weighted lever R⁶ to elevate rod I to a position where it holds the pressure-pulleys G⁵ G⁶ out of contact with the driving-belts, and the said frame in moving away from the cutters, also by means of lever C', applying the gear, which rotates the shaft K' to cause the carriage O to move backward to the starting-point, said gear being released at the end of the return of the carriage by the engagement of the wedge on bar M with the rod holding the pressure-pulley in contact with the reverse-motion belt. 75
